MULTIPLE TRANSFORMING PRINTER

Leon T. Eliel, Pasadena, Calif.

Application April 27, 1936, Serial No. 76,573

7 Claims. (Cl. 88—24)

This invention relates to transforming printers whereby photographs having images which are distorted, by reason of the fact that they have been taken at oblique angles, are corrected in the printing thereof so as to eliminate the distortion of the image and thereby produce a print wherein the various parts of the image are spaced apart in accordance with the true scale relation in which the original parts represented by the image existed at the time the photograph was taken. The invention relates in particular to a transforming printer whereby a plurality of complementary oblique photographs which have been simultaneously taken may be transformed and printed on a single sensitized member, such as a photographic negative.

Herein I use the term "complementary photographs" to indicate two or more photographs simultaneously taken of adjacent sections of an area, and likewise employ the term "complementary images" to mean the images of photographs simultaneously taken of adjacent sections of an area and which, when properly combined in side-by-side relation, will form a complete picture or image of the total area covered by the complementary images. The invention is of especial utility in the art of map making, wherein the terrain is photographed by use of a multiple-lens camera in which the lenses are so placed that they will photograph on separate negatives complementary images of complementary sections of an area of the terrain. It has been the customary practice to print each image of a set of complementary images separately by use of a transforming printer, and then join the separate prints together in side-by-side relation so as to produce a picture of the entire area covered by the set of complementary photographs.

It is an object of the present invention to provide a transforming printer whereby the complementary images of a set of complementary photographs may be printed on a single sensitized member, such as a photographic negative, thereby forming the complete or composite photograph without the necessity of separate prints as has been heretofore necessary.

It is an object of the invention to provide a transforming printer having a rotary head or photograph support with means thereon to carry a plurality of photographs, a rotary print support for carrying a sensitized photographic sheet or plate on which the composite print is to be made, and a lens support carrying a lens in operative position between the photograph support and the print support, with means for support-

ing the foregoing members in such a manner that they may be quickly aligned and so that the positions thereof may be changed at any time to change the focal distances and also the angular relationship of the photograph support and the print support under various selected conditions of operation, such as a change in the focal distance of the lens or the use of the transforming printer with photographs made by a different multiple-lens camera.

It is a further object of the invention to provide a transforming printer of the above character having a removable head or photograph support in duplicate so that one set of complementary images can be printed from photographs held in one of the heads while another set of photographs is being mounted in the other head in preparation for the transforming and printing thereof.

It is a further object of the invention to provide a simple means for holding the photograph or analogous means carrying the distorted complementary images in proper position on the rotary head, together with an improved means for bringing the photographs into practical positions of registration. Multiple-lens cameras of the character employed in aerial photography generally provide registration marks in their margins by means of which the relationship of each individual picture with its lens is recorded. My invention provides an effective means, utilizing these registration marks, for locating the photographs on the rotary head of the transforming printer while the rotary head is removed from the printer, and so that the images of the photographs will all be in proper position for projection in complementary relation onto a sensitized member carried by the print support.

It is a further object of the invention to provide a transforming printer of the above character having a mask disposed adjacent the front surface of the print support, this mask exposing on the face of the sensitized member carried by the print support an area which is to receive the transformed image projected from a distorted image carried by the rotary head. The invention also has as an object thereof to provide a means for adjusting this mask to a high degree of precision.

Illumination control in transforming pictures taken by a multiple-lens camera is very troublesome owing to the fact that the pictures are taken obliquely, one toward the sun, one away from the sun, and two at right angles to it, or some similar arrangement. As the result, at least

three out of four of the pictures taken by a four-lens camera, for example, will be produced under different conditions of lighting, with the result that under ordinary practices of transforming the prints separately and then assembling them to produce the complete picture, great difficulty is experienced in matching up the complementary prints so that the same density within reasonable limits will be obtained in all parts of the complete picture. It is an object of my invention to provide a lighting system for the transforming printer adapted to be adjusted in accordance with the requirement of a complete assembly of complementary photographs carried on the rotary head so that in the printing of the images from these photographs consecutively onto a sensitized member carried by the rotary print support, a practical matching of densities will be accomplished in each of the complementary sections of the completed print.

A further object of the invention is to provide a photoelectric cell for making a final check of the printing lights used in the printing of the respective images from the photographs before these images are printed onto the sensitized member, together with an arrangement whereby the adjoining edges are matched with a high degree of precision by the checking of the printing light through the overlapping edges of the respective complementary images. The result of the foregoing is that the composite prints obtained by the use of my transforming printer are far superior, from the standpoint of color matching and detail matching, to results obtainable when all of the transformations of a set of distorted images are individually transformed and the prints therefrom subsequently trimmed and assembled.

The problem of proper illumination is further complicated by the fact that those sections of the transformations which are enlarged require greater illumination than the sections which are either not enlarged or are reduced in the printing thereof. It is an object of the invention to provide means for light distribution and control which are adjustable so as to compensate for the variations hereinabove set forth.

Further objects and advantages of the invention will be made evident throughout the following part of the specification.

Referring to the drawings, which are for illustrative purposes only,

Fig. 1 is a diagrammatic view showing the relationship of a group of complementary photographs taken by a multiple-lens camera with a photographed area and with the composite picture of such area.

Fig. 2 is a plan view of a preferred form of my transformer.

Fig. 3 is a fragmentary section taken as indicated by the line 3—3 of Fig. 2, but with the head supporting easel turned into a plane perpendicular to the longitudinal axis of the supporting bed plate.

Fig. 4 is a face view of the rotary head, viewed as indicated by the line 4—4 of Fig. 3.

Fig. 5 is a fragmentary elevational view taken as indicated by the line 5—5 of Fig. 4.

Fig. 6 is an enlarged sectional view taken on a plane indicated by the line 6—6 of Fig. 4.

Fig. 7 is an enlarged plan view of the adjusting jig in place on the rotary head.

Fig. 8 is a sectional view taken substantially as indicated by the line 8—8 of Fig. 7.

Fig. 9 is a plan view of the adjusting jig with

the telescope holder thereof removed so as to show the underlying parts and the manner in which engagement with the plate holder is made.

Fig. 10 is a fragmentary section taken as indicated by the line 10—10 of Fig. 7.

Fig. 11 is a partly sectioned elevational view of the printing head easel.

Fig. 12 is a face view taken substantially as indicated by the line 12—12 of Fig. 11.

Fig. 13 is an enlarged fragmentary sectional view taken as indicated by the line 13—13 of Fig. 12.

Fig. 14 is an enlarged fragmentary section taken on the plane 14—14 of Fig. 12.

Fig. 15 is a fragmentary, partly sectioned view showing the means which I employ for checking the projected light through use of a photoelectric cell.

Fig. 16 is a sectional view taken as indicated by the line 16—16 of Fig. 15.

Fig. 17 is an electrical diagram showing the means for controlling the printing light.

In Fig. 1, which is purely schematic, I show an area 21, consisting of complementary areas A, B, C, and D, which is to be photographed. This area 21 may be a portion of a terrain which, to the eyes of a person in a position of elevation thereabove, presents a picture. This area 21 may be of such size that it cannot be suitably photographed through a single lens; therefore, to produce a picture thereof, a multiple-lens camera is employed.

Although the multiple-lens camera used may have various numbers of lenses, I shall in this description of the adaptability of the invention limit the description to the use of a four-lens camera 22 having four negative plates or films A', B', C', and D' adapted to respectively receive the images of the areas A, B, C, and D. Owing to the fact that the optical axes on which the negatives A', B', C', and D' are photographed are oblique, the areas photographed upon the negatives A', B', C', and D' will be of the character of the respective areas a', b', c', and d' indicated by dotted lines in Fig. 1, and which radiate from a common center P. Further, in view of the oblique setting of the negatives A', B', C', and D' relative to the surface of the terrain, the complementary areas A, B, C, and D will be each represented on the negatives A', B', C', and D' by distorted images indicated by dotted lines 23. It is well known that in order to produce a rectified picture of the area 21, or pictures of the areas A, B, C, and D, it is necessary to use a transforming printer, wherein the negative and the sensitized member on which the print is to be made are disposed at predetermined angles so that the images projected onto the plane in which the sensitized member is held will be of the shape of the area a', b', c', or d' originally photographed.

In Fig. 2 I show a photograph A' which may be the negative transparency indicated in Fig. 1 or may be a positive transparency directly printed therefrom. This member A' is mounted on a rotary head 23 in such position that light may be projected therethrough and along a path indicated by dotted lines 24 to a lens 25 by which the image is projected forwardly, as indicated by dotted lines 26, to a plate or sheet of sensitized material 27 mounted on a rotary print holder 28, the members 23, 25, and 28 being disposed in the proper angular relationship for transforming the image of the member A' in the printing thereof on the sensitized member 27. If the member A' 75

shown in Fig. 2 carries a negative image, the transformed print obtained on the sensitized member 27 will be a positive print. It is customary in practice, however, to prepare positive photographs by direct contact from the negative taken from the aerial camera, so that the print obtained on the sensitized member 27 will be a negative print from which a positive direct print is subsequently made. The transformer shown 5 in Fig. 2, and the succeeding figures, includes a cast bed plate 29 having a table 31 formed at the rearward end thereof in permanently fixed relation, and having mounted thereon adjustable tables 32 and 33 respectively supporting the rotary head 23 and an easel 49 carrying the lens 25. As best shown in Figs. 2 and 3, the adjustable tables 32 and 33 each have a horizontal wall 35 and oppositely disposed, downwardly projecting side walls 36 at the edges of the horizontal wall 20 35. Each table 32 or 33 is adjustable in all directions on the bed plate 29. For example, there are vertical screws 37 threaded through the horizontal wall 35 and having plates 38 at the lower ends thereof for engaging the upper wall 39 of the bed plate 29, as shown in Fig. 3, and in the side walls 36 there are side screws 41 for engaging the side faces 42 of the bed plate 29. At the forward and rearward ends of each table 32 and 33 are hold-down brackets 43 which are bolted 25 to the upper wall 39 of the bed plate 29 by use of bolts 44. Each of the brackets 43 has a vertical wall 45 and an inwardly extending wall 46 projecting over a portion of the associated table 32 or 33. In each of the vertical walls 45 there are two adjusting screws 47 adapted to engage an edge of the table 32 or 33, and through each wall 46 there is a hold-down screw 48 adapted to engage the table with which each bracket is associated. Mounted on the upper face of the table 40 32, as shown in Fig. 3, there is a head supporting easel 49 having a base portion 51 which may be prepared so that the easel may be swung on a vertical axis, by using slots 52 through which to extend studs 53 by which the easel 49 is secured 45 to the table 32.

The upper end of the easel 49 has a horizontal bore 54 in which a forwardly projecting stub shaft 55 is secured, which may be by use of a pin 56. The stub shaft 55 has an axial bore 57 with 50 a counterbore 58 at the rearward or leftward end thereof for receiving a compression spring 59 in position to engage the head 61 of a bar 62 which extends through the bore 57 and the counterbore 58 of the stub shaft 55. A plate 63 is secured by screws 64 to the leftward end of the stub shaft 55, and this plate 63 has an opening 65 through which an end 66 of the bar 62 projects. On the forward or rightward end of the bar 62 there is a transverse pin 68 adapted to engage diametrically 55 opposed depressions 69 in the front face of a cap 71 having an opening 72 through which the end 67 of the bar 62 may pass, and likewise having transverse notches 73 radiating from the opening 72 and being of such size that the ends of the pin 68 may pass therethrough when the cap 71 is rotated through an angle of 90° from the position in which it is shown so that the notches 73 are in alignment with the ends of the pin 68. The rotary head 23, which is essentially a circular disc, 60 has a hub 74 with a bore 75 adapted to closely fit the shaft 55. It is the function of the cap 71 to hold the hub 74 against the shoulder 76 at the upper end of the easel 49. With the cap 71 removed from the position in which it is shown, the 65 rotary head 23 is placed upon the stub shaft 55.

Then, by rightward pressure against the projecting end 66 of the bar 62, such bar is moved rightwardly against the force of the spring 59 so that the rightward end of the bar 62 will move into the position indicated by dotted lines 77. The cap 71 is then slipped over the rightward end 67 of the bar 62 and past the ends of the pin 68, whereupon the cap 71 is rotated so as to bring the depressions 69 into alignment with the ends of the pin 68, and the pressure against the leftward end 66 of the bar 62 is released so that the spring 59 will force the bar 62 leftwardly and will transmit a leftward force through the pin 68 and the cap 71 to the hub 74 of the rotary head 23 to hold such rotary head against the shoulder 76. 15

The rotary head 23 has a number of openings 78 therein corresponding to the number of photographic plates to be transformed onto a single print. In the present instance, where the invention is being used with a four-coupled aerial 20 camera, there are four of such openings 78 evenly spaced around the center of rotation of the rotary head 23 defined by the stub shaft 55. In Fig. 4 I have shown the rotary head with one of the openings 78 exposed and with photograph 25 supporting means 79 secured in operative relation to other of the openings 78. As shown in Figs. 3 to 6 inclusive, each of the photograph supports has a base frame 81 consisting of four side members 82 from which lips or shelves 83 30 project inwardly so that a photographic plate 84, or other image carrying transparency, may be supported thereon, as shown in Fig. 6. To hold the photographic plates 84 in place in the base frame 81, cover frames 85 are provided which are 35 essentially the same size as the base frame 81. Each cover frame 85 carries an optical flat glass 36 having downwardly converging edge faces 87 engaging the frames 85 and 81 in the manner shown in Fig. 6. The lower face 88 of each glass 40 45 36 may bear directly against the photographic plate 84, or a piece of transparent material 89, such as Celluloid, may be placed between the face 88 and the upper face of the member 84 to prevent the face 88 from becoming scratched. The glasses 36 are held in the cover frames 85 by means of small plates or clips 91 which are secured by means of screws 92 so as to project over the edges of the plates 36. 45

The photograph supporting means 79 are adjustably secured in place by means of lugs 93, two of which project from each base frame 81. Each lug has an opening 94 therein through which a stud 95, of considerably smaller diameter, may project from the face of the rotary head 23 55 in the manner shown in Fig. 5. Each stud 95 has a nut 96 threaded thereon, adapted to force a washer 97 downwardly against the upper face of a lug 93 so as to clamp the lug 93 tightly against the face of the rotary head 23. Prior to 60 the tightening of the nut 96, the photograph holding means 79 may be adjusted on the face of the rotary head 23 within reasonable limits. 55

As shown at the top and right-hand side of Fig. 4, each base frame 81 has lugs 98 projecting 65 outwardly therefrom to which leaf springs 99 are pivotally secured by such means as screws 101, so that they may be swung outwardly as shown. Each cover frame 85, as shown at the left-hand side of Fig. 4 and also in Figs. 5 and 6, 70 75 has lugs 102 projecting outwardly near the corners thereof and in such positions that when the leaf springs 99 are swung inwardly, the free ends thereof may be rested upon the lugs 102 to apply downwardly pressure to hold the cover frames 85 75

in position on the base frames 81. In order to apply the leaf springs 99 to the lugs 102, it is necessary to flex the ends thereof outwardly from the face of the head 23, thereby placing a strain 5 therein.

The camera by which the complementary photographs are obtained has therein means for producing registration marks in the edge portions of the photographic plates A', B', C', and D'. 10 After the photographic plates are mounted in the supporting means 79, the supporting means are adjusted upon the face of the rotary head 23 so as to bring the registration marks into a definite relationship to the axis of rotation of 15 the head 23, with the result that when the head 23 is mounted on the stubshaft 55, each photographic plate may, by rotation of the head 23, be brought into a predetermined position of alignment with the lens 25 shown in Fig. 2. For 20 this purpose I provide an adjujusting jig 103 which is shown in Figs. 7 to 10 inclusive, this adjusting jig 103 being used while the rotary head is lying flat on a suitable table or support. The jig 103 has a lower plate 104, which is shown in plan view in Fig. 9, and has an upper plate 105 superimposed on the lower plate 104, as shown in Fig. 7. The lower plate 104 is supported in raised relation to the face of the rotary head 23 by means of legs 106, Figs. 8 and 10, and a bored 25 boss 107 adapted to fit over the hub 74 of the rotary table 23. The upper plate 105 is supported in raised relation to the lower plate 104 by means of legs 108 which project downwardly from the upper plate 105 and are internally threaded at 30 their lower ends to receive studs 109 by which they are firmly secured to the lower plate 104.

In addition to the bored boss 107, the lower plate 104 has means for definitely positioning the 40 jig 103, such additional means consisting of a pin 111, Figs. 9 and 10, which projects downwardly from an extension 112 of the lower plate 104 into an opening 113 provided in quadruplicate in the rotary head 23 for the purpose of registration, all of these registration openings 113 being 45 shown in Fig. 4. There is an opening 114 in the lower plate 104 having a diameter slightly greater than the width of the photograph supporting member 79 which lies beneath the lower plate 104, as shown in Figs. 8 and 9. On the upper face of the lower plate 104 there is a sliding frame 115 having two side walls 116 disposed at right angles to each other, and within the sliding frame 115 a rotating frame 117 is disposed, this rotating frame being circular, as 50 shown in Fig. 9, and being held in place by means of washers 118 which are secured to the sliding frame 115 by means of screws 119. Integrally formed fingers 121, four in number, project downwardly from the rotatable frame 117 through the opening 114 in the lower plate 104 so as to engage the four sides of the photograph 55 holding means 79 over which the jig 103 may be placed. By rotating the rotatable frame 117, rotation may be transmitted to the photograph 60 supporting means 79 so as to rotate the same on the surface of the rotary head 23. Rotation of the frame 117 may be accomplished by means of thumb screws 122 which are threaded through the slidable frame 115 in tangential relation to 65 the rotatable frame 117 so as to engage members 123 which project radially from the rotatable member 117, as shown in Fig. 9.

Means are provided for moving the slidable frame in any direction in a plane parallel to the 70 upper face of the lower plate 104, such means

consisting of a pair of plates 124 which are secured in a slidable manner to the walls 116 of the slidable frame, and adjusting screws 125 which engage internally threaded bosses 126 formed on the outer faces of the plates 124. Each plate 124 has a pair of horizontal slots 127 therein through which screws 128 project into threaded engagement with the cooperating side wall 116 of the slidable frame 115. The adjusting screws 125 extend through openings 129 formed in walls 131 which project upwardly from the lower plate 104. The adjusting screws 125 are prevented from longitudinal movement relative to the walls 131 by means of washers 132 disposed on opposite sides of the walls 131 and 15 held thereagainst by means of cotter pins 133 which pass through the screws 125 in the manner shown in Fig. 9. When the screws are rotated, the threads 134 thereon cause the plates 124 to move along lines defined by the axes of the screws 125, the walls 116 of the sliding frame 115 slanting along the plates 124 as the frame 115 is moved. By turning one screw 125 at a time, the frame 115 may be caused to move in the direction of the axis of the screw turned, but by a 20 simultaneous rotation of the screws 125, a resultant movement along the horizontal line disposed at an angle to the axis of each screw 125 may be obtained. By a proper use of the screws 122 and 125, an adjusting movement is imparted 25 through the fingers 121 to the film holding means 79, and after the proper position of adjustment of the member 79 is obtained, it is locked in place by tightening the nuts 96 so that the base frames 81 will be clamped to the face of the rotary 30 head 23.

As shown in Figs. 7 and 8, the upper plate 105 carries a plurality of telescopes 135 which are adjustably supported on the upper plate 105 by means of telescope supports 136, each of which 40 includes an adjustable plate 137 and an eccentric 138 supported at its inner end, which eccentric 138 carries a telescope 135. As best shown at the left side of Fig. 7, the plate 137 of each telescope support 136 has an opening 139 adapted 45 to closely fit a stud 141 which projects upwardly from the upper plate 105 and a larger opening 142 through which a stud 143 projects upwardly from the upper plate 105. Washers 144 and nuts 145 are applied to the threads of the studs 141 50 and 143 to clamp the plates 137 against the upper plate 105. Extending outwardly from each of the plates 137 is a lever 146, adapted to be engaged on opposite sides by adjusting screws 147 which are threaded through lugs or walls 148 55 formed on the upper face of the upper plate 105. When the nuts 145 are loosened on the studs 141 and 143, the adjusting screws 147 may be employed to rotate the plate 137 on the stud 141, thereby causing a movement of the associated 60 telescope 135 in a plane parallel to the plane defined by the plate 105, or across the face of a photographic plate A', Fig. 9, having an index part 149 thereon. Movement of each telescope toward or away from the center of the opening 65 151 of the upper plate 105 may be accomplished by turning its supporting eccentric 138, which may be clamped in place after it has been properly adjusted by use of a clamping screw 152. After a photographic plate, such as the member 70 A' of Fig. 9, is properly mounted on the rotary head 23 so that the image projected therefrom will strike the sensitized member 27 of Fig. 2 in the proper position, the jig 103 may be placed 75 over the holding means 79 of the photographic 75

member A', and the telescopes 135 of the jig may be adjusted so as to bring the cross lines 153 thereof, which are projected in dotted lines in Fig. 9, into registration with the registration marks 149. After being so adjusted, the telescopes 135 are locked in position, and thereafter the adjusting of the supporting means 79 to bring the photographic plates into proper position on the rotary head 23 is accomplished by use of the jig 103 which is consecutively placed over each of the photograph holders, so that while the jig 103 is so placed the adjusting screws 122 and 125 may be operated to move the supporting means 79 in such direction or directions that the registration points on the photographic member held thereby are brought into register with the cross lines 153 of the telescopes of the jig 103.

When the rotary head 23 is mounted in operative position on the easel 49, as shown in Figs. 2 and 3, the registration or aligning openings 113 of the rotary head 23 are employed to position the rotary head 23 so that the photographic plates carrying the distorted images may be successively brought into exact positions of cooperation with the lens 25. For this purpose a bracket 154, Fig. 3, is mounted on the easel 49, this bracket having a horizontal opening 155 through which a pin 156 extends, such pin 156 being movable back and forth into and out of engagement with the successive registration openings 113 when the rotary head 23 is rotated from one position to another.

As shown in Figs. 2, 11, and 12, the rotary print holder 28 comprises a metal disc having a rearwardly extending hub 157 which rotates in the bore 158 of an easel or standard 159 having a base plate 161 so that it may be secured to the table 31 of the base plate 29 by means of studs 162 and nuts 163. The sensitized sheet 27 which is to form the transformed print may, in accordance with the practice of the invention, be a sheet of sensitized photographic paper or may be a transparency with a sensitized photographic emulsion thereon. In the present instance the member 27 is square and is to receive four complementary images thereon, such images being disposed around the center of the member 27 as defined by the axis of rotation of the print supporting head 28. To hold the member 27 against the front face of the member 28, a grille of crossing channels 164 is provided, such channels 164 being connected to a central opening 165, Fig. 11, which projects within the hub 157 of the member 27 and communicates through radial openings 166 with a channel 167 formed in the bore 158, such channel 167 being connected to an exhaust pump through a tube 168. The tube 168 may be provided with a suitable two-way valve 169 for control of and release of the vacuum to be applied to the channels 164 of the member 28.

By means of a registration pin 171, carried on the easel 159 by means of a bracket 172, a dividing of the rotary print holder 28 into a desired number of divisions or sections is accomplished. In the present instance the member 28 and the sensitized member 27 supported thereby are to be divided into four sections, which is accomplished by providing the member 28 with four evenly spaced registration openings 173 in positions to be consecutively engaged by the leftward end of the pin 171, as best shown in Fig. 11. A mask 174 is provided to cover three quarters of the sensitized member 27 and to leave a quarter section 175 thereof exposed. This mask is adapted to be rotated from the position in which

it is shown in full lines in Fig. 11 against the face of the sensitized member 27, into a retracted position indicated by dotted lines 176. The mask 174 has a plate portion 177 with a notch 178 at the rightward side thereof, as viewed in Fig. 12. To the edge walls 179 of the plate 177 forming the notch 178, adjustable edge strips 181 are secured by means of screws 182, as shown in Fig. 14. These edge strips 181 have accurately ground knife edges 183 which, by adjustment of the edge strips 181, may be caused to lie exactly on lines diverging at an angle of 90°. With the knife edges 183 disposed at an angle of exactly 90°, the mask 174 may be adjusted so that the point of meeting of the inner ends of the knife edges 183 will coincide with the axis of rotation p of the rotary member 28, which axis p will pass through the exact center of the print formed on the sensitized member 27. A small saw cut 180 on the member 183 is radially disposed at point p, so that a center cross will be formed on the transformation 27, and notches 190 on the member 183 provide registration marks on the transformation by means of which principal point p may also be located.

The mask 174 may be adjusted in all directions by use of the following means. A bracket 184 is secured to the lower part of the easel 159 in forwardly extending relation, this bracket having a threaded bore 185, Fig. 12, centralized on a horizontal axis which is likewise parallel to the plane defined by the front face of the rotary member 28. Threaded into the bore 185 are laterally adjustable sleeves 186 which serve as bearings for a shaft 187 having outwardly extending squared ends 188 which support legs 189 of a connector plate 191 which is adjustably secured to the lower portion of the plate 177 by means of screws 192 which pass through enlarged openings 193 in the member 191. Adjusting screws 194 are mounted on opposite sides of a notch 195 in the member 191, through which notch 195 a lug 196 projects from the plate 177. The legs 189 of the plate 191 have bosses 197 at the lower ends thereof with squared openings 198 therethrough, through which the squared ends 188 of the shaft 187 extend.

Perpendicular adjustment screws 199 are threaded through the walls of the bosses 197 into engagement with plates 201 which fit against the upper and lower faces of the squared shaft 188, and end plates 202 having rectangular openings 203 therein are fitted on the outer ends of the squared shaft ends 188, these end plates 202 having horizontal adjusting screws 204 adapted to bear against the opposing horizontal faces of the squared shaft ends 188 in the manner best shown in Fig. 11. The end plates 202 have vertical slots 205 in the upper and lower portions thereof, which slots 205 receive horizontal pins 206 which are projected outwardly from the bosses 197. Washers 207 and nuts 208 are applied to the outer ends of the squared shaft portions 188, and spacing plates or washers 209 are disposed between the inner faces of the bosses 197 and the ends of the sleeves 186, as shown in Fig. 12. The foregoing arrangement of parts may be employed to adjust the mask 174 in any desired direction so as to bring the point of meeting of the knife edges 183 into registration with the axis p.

The image projected by the lens 25 from the photographic member, such as A' aligned therewith, will have a shape somewhat of the character indicated by dotted lines 211 of Fig. 12. The

two inner edge portions of the image 211 will be cut off by the mask 174, and the outer edge portions 212 of the image 211 will fall beyond the edges 213 of the sensitized member 27. The 5 knife edges 183 accurately define the lines of division or engagement of the complementary images received by the sensitized member 27, these images meeting accurately on the lines of division without overlapping or without unexposed strips therebetween.

As indicated by dotted lines 214 in Fig. 2, a light box or housing 214 is mounted behind the rotary head 23 in alignment with the axis of the lens 25 so that light will be produced behind the 15 photographic plate A', or other photographic plate aligned with the lens 25. The lamp housing 214 carries a group of electric lamps adapted to be individually adjusted. In the present practice of the invention I employ six lamps L₁ to L₆ inclusive as shown in Fig. 17 which may be distributed within the light housing 214 in a manner which may be readily determined by experimentation. Each lamp has four adjustable, separately and selectively used controls 20 which may be adjusted with respect to the four photographic plates A', B', C', and D' before the sensitized member 27 is placed on the head 28. To accomplish this control, I provide a control panel 215 having four sections S₁, S₂, S₃, and S₄ across which conductors 216 extend from the lamps L₁ to L₆ inclusive, the other sides of these lamps being connected through conductors 217 with a common conductor 218 leading to a source of electric current such as a generator 219. Each 30 section S₁ to S₄ inclusive has six rheostats R₁ to R₆ inclusive, all being connected to a common conductor 220 which leads to the generator 219, and each rheostat R₁ to R₆ being connectable through a switch 221 with a conductor 216 leading 35 to a corresponding lamp of the group of lamps L₁ to L₆. There are six of the switches 221 in each section, and all of the switches 221 of each group are adapted to be simultaneously closed and opened so as to close electric circuits including the lamps L₁ to L₆ inclusive and the 40 associated group of rheostats R₁ to R₆ inclusive. This is accomplished by the use of four solenoids 222 connected by conductors 223 with a common conductor 224 leading to the side of the generator 219 to which the conductor 218 45 is attached, and being connectable through manually operable switches 225 with the common conductor 220. The selective operation of the switches 225 accomplishes a selective bringing of the groups of rheostats in the sections S₁ to S₄ into circuits including the lamps L₁ to L₆ and the generator 219.

Four complementary photographic plates are mounted on the rotary head 23, and the individual sections of rheostats are adjusted in accordance with the light requirements of each photographic plate before the sensitized member 27 is mounted on the rotary support 28. Each section of rheostats S₁ to S₄ is adjusted independently of the remaining sections and entirely in accordance with the strength and distribution of light required by the photographic plate to which the section of rheostats corresponds in the operation of the transforming printer. In this manner such variations in density existing in and between the photographic plates is compensated for, with the result that a practical control of the densities of the complementary images obtained on the print formed 70 from the sensitized member is attained. It is

an especial feature of the invention to provide means for precisely controlling the lighting of the adjacent or matching edges of the complementary images projected onto the sensitized member 27. This I accomplish by the use of a light measuring device 226, Fig. 15, which operates in conjunction with means 227 for projecting desired portions of the images projected by the lens 27 to the light responsive and measuring device 226.

It will be understood that the transforming printer is preferably to be used in a dark room and that portions thereof may be housed-in as required to protect the sensitized member 27 from light other than the image projected thereon by the lens 25. As indicated by dotted lines in Fig. 2, a wall 228 may be placed across the front of the easel 34 so that the lens structure 25 may project therethrough. As shown in Fig. 15, the light responsive device 226 may be mounted on the wall 228 adjacent the forward end of the lens 25, and the image projecting means 227 may be mounted on the wall 228 by means of a bracket 229 so that it may be swung from a retracted position indicated by dotted lines 231 into a position before the lens 25, as indicated 10 in full lines.

The member 227 has a front wall 232 carrying a lens 233 adapted to be aligned with the objective lens 25, a diagonal wall 234 carrying a plane reflecting mirror 235 which will project the image from the lens 233 toward a lens system 236 carried by a side wall 237 of the device 227 in such position that it will direct the image to a photoelectric cell 238 forming a part of the light responsive means 226. The use of a photoelectric cell for the measurement of light is old. Accordingly, the light responsive means 226 has been shown diagrammatically. For the present purposes the light responsive means 226 is shown 30 with an ampere meter 239 adapted to be placed at a point convenient to the operator of the transforming printer and to be connected to the remaining electrical parts of the device 226 by means of conductors 241, this meter 239 having 35 an indicator 242 which moves in accordance with the light received by the photoelectric cell 238.

As shown in Fig. 16, the side wall 237 of the device 227 has a mask 243 mounted thereon so as to partly cover the area of the lens system 236. 50 This mask has two slots or openings 244 therein through which the matching edge portions of the images projected from the lens 25 may pass to the lens system 236 under control of shutters 245 and 246 which are interconnected in such a manner 55 that when the shutter 246 closes the lower opening 244, the shutter 245 will expose the upper opening 244 of the mask 243. The shutter 245 consists of a metal strip having its inner end 247 hinged on a pivot 248 which may be mounted on the mask 243. The rightward or outer end of the shutter 245 has a slot 249 therein and a projecting handle 251 whereby the shutter may be raised and lowered. The lower shutter 246 is mounted on a pivot 252 disposed at its inner end and has a pin 60 253 at its outer end which engages the slot 249 in the shutter 245. When the shutter 245 is raised, the engagement of the pin 253 with the slot 249 will raise the shutter 246 into closed position relative to the lower mask opening 244, and as the shutter 245 is swung downwardly into closed position relative to the upper mask opening 244, as indicated by dotted lines 254, the shutter 246 will be swung into lowered position, or open relation to the lower mask opening 244, as 65 70 75 80 85 90 95 98

indicated by dotted lines 255. An auxiliary mask 256 is provided which may be swung on a pivot 257 from the open position in which it is shown in full lines to closed position indicated by dotted lines 258 wherein it will cover the inner halves of both upper and lower mask openings 244.

As shown in the schematic Fig. 1, the portions or images *a'*, *b'*, *c'*, and *d'* of the terrain which are projected photographically to the respective photographic plates *A'*, *B'*, *C'*, and *D'* have overlapping edge areas 259. The transformed images which are projected from the photographic plates in the transforming printer and onto the sensitized member 27 are of the same shape as the areas *a'*, *b'*, *c'*, and *d'* of Fig. 1, as indicated by the image 211 shown in dotted lines in Fig. 12. With relation to the transformed images, and likewise with relation to the original images *a'*, *b'*, *c'*, and *d'*, the mask openings 244 correspond to the overlapping areas 259 at the edges of the images. Accordingly, in preparation for the printing of the complementary images on the sensitized member 27, each photographic plate, such as the plate *A'* shown in Fig. 2, is moved into printing position, and by use of lights obtained from the lamps *L₁* to *L₆* inclusive, the image thereof is projected onto a sheet of paper carried on the face of the rotary member 28. The rheostats *R₁* to *R₆* in the control section corresponding to the photographic plate at this time in alignment with the lens 25 are given an initial adjustment while the intensity and distribution of light on the paper carried by the rotary member 28 is visually checked. The member 227 may be then swung from its retracted position shown in dotted lines 231 of Fig. 15 into full line position, and the matching edge areas of the image may be individually checked by use of the photoelectric cell 238. With the auxiliary mask 256 in retracted position as shown in full lines in Fig. 16, the upper matching edge area of the projected image is permitted to pass through the upper mask opening 244, whereupon the reading of the meter 239 is noted. The handle 251 of the shutter 245 is then swung downwardly so that the lower mask opening 244 will be opened and the upper opening 244 closed, whereupon the quantity of light constituting the lower matching edge area of the image may be noted on the meter 239. If there is a discrepancy between these readings, or, in other words, a deviation from a standard reading, the rheostats at this time connected with the lamps *L₁* to *L₆* inclusive may be readjusted to balance the light passed through the upper and lower mask openings 244. Two like readings obtained through the upper and lower openings 244 and 245 of the mask 243, with the auxiliary mask 256 in retracted position, indicate only that the quantities of light passed through the openings 244 are the same, but do not show whether or not the light at the inner end of an opening 244 may be stronger or weaker than the light at the outer end of the opening. To determine whether the light passing through the inner and outer halves of the openings 244 is balanced, the auxiliary shutter 256 is moved into the position in which it is indicated in dotted lines 258, wherein the inner halves of each of the openings 244 are covered. Light is then projected through the remaining or outer portions of the openings 244 by use of the shutters 245 and 246 as previously described, and the lights adjusted until the reading is the same on both outer portions. At the conclusion of the balancing of the complementary whole

strips and half strips the total illumination of the strips is identical and the illumination of the half strips is identical, thereby providing for identical illumination along the matching lines.

It will be apparent that the lamps *L₁* to *L₆* inclusive comprise a bank of lamps that, by virtue of the control system indicated in Fig. 17, is adjustable with respect to the pattern of intensity in cross-section of the light projected from the bank, and that such a bank of lamps may be adjusted for a beam pattern so related to the pattern of the light-transmitting character of the photographic plate as to produce a desired distribution of intensity over the image cast on the printing member. Thus, if it is desired to have an image of substantially uniform intensity, the bank of lamps will be adjusted to project a beam having a cross-sectional pattern of light intensity substantially complementary to the pattern of the light-transmitting character of the photographic plate. The required adjustment of the projected light beam is possible because each individual lamp of the bank projects its own beam and the beam from the bank as a whole is a combination of these individual beams. With the light measuring means described, it is conveniently possible to measure the light intensity of selected portions of the image to determine the particular pattern of light beam projected from the bank of lamps that will be required to give the desired effect at the printing member of the apparatus.

After adjustment of each of the sections *S₁* to *S₄*, inclusive, of the rheostats *R*, the sensitized member 27 may be placed on the rotary member 28, and the complementary images carried by the photographic plates held on the rotary member 23 may be consecutively projected onto consecutive portions of the sensitized member 27 while the mask 174 is in raised position as shown in Figs. 2, 11, and 12. This consecutive projection of the images so that they will become consecutively printed on the sensitized member 27 is accomplished by consecutively rotating the head 23 and the print supporting member 26 from position to position, and using the different sections of rheostats *S₁* to *S₄* with the respective photographic plates for which they have been adjusted.

Although I have herein shown and described my invention in simple and practical form, it is recognized that certain parts or elements thereof are representative of other parts, elements, or mechanisms which may be used in substantially the same manner to accomplish substantially the same results; therefore, it is to be understood that the invention is now to be limited to the details disclosed herein but is to be accorded the full scope of the following claims.

I claim as my invention:

1. In a photographic printer for printing contiguous complementary images on a single light sensitive member from a plurality of complementary photographic members to produce a consolidated print, the combination of: supporting means for said plurality of photographic members; supporting means for said light sensitive member; a light source and an optical system by which printing light can be transmitted successively through said photographic members upon corresponding areas of said light sensitive member; means for varying the intensity and cross sectional pattern of said printing light to compensate for varying densities of said photographic members; a light intensity indicating

- device positioned upon said printer, including an element movable into and out of the path of said light, for measuring the intensity of the light transmitted through each individual photographic member; and means for restricting the light reaching said device to that transmitted through selected areas of said individual photographic member to indicate the variation of the cross sectional pattern of said printing light which will match the contiguous margins of the individual images printed upon said light sensitive member when projected thereon, so that the photographic members can be successively printed upon said light sensitive member to produce a print having substantially uniform density.

2. In a photographic printer for printing contiguous complementary images on a single light sensitive member from a plurality of complementary photographic members to produce a consolidated print, the combination of: supporting means for said plurality of photographic members; supporting means for said light sensitive member; a light source and an optical system by which printing light can be transmitted successively through said photographic members upon corresponding areas of said light sensitive member; an individual control means corresponding to each said photographic member for varying the intensity and cross sectional pattern of said light to compensate for varying densities of said photographic members; a light intensity indicating device positioned upon said printer, including an element movable into and out of the path of said light, for measuring the intensity of the light transmitted through each individual photographic member; and means for restricting the light reaching said device to that transmitted through selected areas of said individual photographic member to indicate the variation of the cross sectional pattern of said printing light which will match the contiguous margins of the individual images printed upon said light sensitive member when projected thereon, so that the photographic members can be successively printed upon said light sensitive member to produce a print having substantially uniform density.

3. In a photographic printer for printing contiguous complementary images on a single light sensitive member from a plurality of complementary photographic members to produce a consolidated print, the combination of: supporting means for said plurality of photographic members; supporting means for said light sensitive member; a light source and an optical system by which printing light can be transmitted successively through said photographic members upon corresponding areas of said light sensitive member; means for varying the intensity and cross sectional pattern of said light to compensate for varying densities of said photographic members; a light intensity indicating device positioned upon said printer, including an element movable into and out of the path of said light, for measuring the intensity of the light transmitted through each individual photographic member; and mask means movable into and out of the light path for restricting the light reaching said device to that transmitted through selected marginal areas of said individual photographic member to indicate the variation of the cross sectional pattern of said printing light which will match the contiguous margins of the individual images printed upon said light sensitive member when projected thereon, so that the photographic members can be successively printed upon said light sensitive member to produce a print having substantially uniform density.

4. In a photographic printer for printing contiguous complementary images on a single light sensitive member from a plurality of complementary photographic members to produce a consolidated print, the combination of: supporting means for said plurality of photographic members; supporting means for said light sensitive member; and an optical system and a light source including a plurality of lamps by which printing light can be transmitted successively through said photographic members upon corresponding areas of said light sensitive member; means for varying the energization of each of said lamps to vary the intensity and cross sectional pattern of said light to compensate for varying densities of said photographic members; a light intensity indicating device positioned upon said printer, including an element movable into and out of the path of said light, for measuring the intensity of the light transmitted through each individual photographic member; and means for restricting the light reaching said device to that transmitted through selected areas of said individual photographic member to indicate the variation of the cross sectional pattern of said printing light which will match the contiguous margins of the individual images printed upon said light sensitive member when projected thereon, so that the photographic members can be successively printed upon said light sensitive member to produce a print having substantially uniform density.

5. In a photographic printer for printing contiguous complementary images on a single light sensitive member from a plurality of complementary photographic members to produce a consolidated print, the combination of: supporting means for said plurality of photographic members, supporting means for said light sensitive member; a light source and an optical system by which printing light can be transmitted successively through said photographic members upon corresponding areas of said light sensitive member; a presettable control means corresponding to each said photographic member for varying the intensity and cross sectional pattern of said light to compensate for varying densities of said photographic member; a light intensity indicating device positioned upon said printer, including an element movable into and out of the light path, for measuring the intensity of the light transmitted through each individual photographic member; and means for restricting the light reaching said device to that transmitted through selected areas of said individual photographic member to indicate which setting of the corresponding control means will vary the cross sectional pattern of said printing light to match the contiguous margins of the individual images printed upon said light sensitive member when projected thereon, so that said control means can be preset and successively operated and the corresponding photographic members successively printed upon said light sensitive member to produce a print having substantially uniform density.

6. In a photographic printer for printing contiguous complementary images on a single light sensitive member from a plurality of complementary photographic members to produce a

consolidated print, the combination of: supporting means for said plurality of photographic members; supporting means for said light sensitive member; and an optical system and a light source including a plurality of lamps by which printing light can be transmitted successively through said photographic members upon corresponding areas of said light sensitive member; presetable control means corresponding to each 5 photographic member for varying the energization of each of said lamps to vary the intensity and cross sectional pattern of said light to compensate for varying densities of said photographic members; a light intensity indicating device, including an element movable into and out of the path of said light, for measuring the intensity of the light transmitted through each individual photographic member; and means for restricting the light reaching said device to that transmitted through selected areas of said individual photographic member to indicate which setting 10 of said control means will vary the cross sectional pattern of said printing light to match the contiguous margins of the individual images 15 printed upon said light sensitive member when projected thereon, so that the control means can be preset and successively operated and the corresponding photographic members successively printed upon said light sensitive member to produce a print having substantially uniform density.

7. In a photographic printer for printing contiguous complementary images on a single light sensitive member from a plurality of complementary photographic members to produce a 20

consolidated print, the combination of: supporting means for said plurality of photographic members; supporting means for said light sensitive member; an optical system and a light source including a plurality of lamps by which printing 5 light can be transmitted successively through said photographic members upon corresponding areas of said light sensitive member; presetable control means corresponding to each said photographic member, each control means including 10 a presetable means for each of said lamps for varying the energization of each of said lamps to vary the intensity and cross sectional pattern of said light to compensate for varying densities of said photographic members; a light intensity indicating device positioned upon said printer, including an element movable into and out of the path of said light, for measuring the intensity of the light transmitted through each individual photographic member; and mask 20 means for restricting the light reaching said device to that transmitted through selected areas of said individual photographic member to indicate which setting of the resistors of each control means will vary the cross sectional pattern 25 of said printing light to match the contiguous margins of the individual images printed upon said light sensitive member when projected thereon, so that the control means can be preset and successively operated and the corresponding photographic members successively printed upon said light sensitive member to produce a print having substantially uniform density.

LEON T. ELIEL. 35
